DESIGN FOR A PHONOGRAPH RECORD RACK

Harry Colburn, Detroit, Mich.

Application January 7, 1943, Serial No. 109,215

Term of patent 14 years

To all whom it may concern:

Be it known that I, Harry Colburn, a citizen of the United States, residing at Detroit, in the county of Wayne and State of Michigan, have invented a new, original, and ornamental Design for a Phonograph Record Rack, of which the following is a specification, reference being had to the accompanying drawing, forming part thereof.

The dominant feature of my design resides in the portions shown in full lines in the drawing.

I claim:

The ornamental design for a phonograph record rack, as shown and described.

HARRY COLEBURN.
